UNITED STATES PATENT OFFICE.

CHARLES V. HUGO, OF ST. LOUIS, MISSOURI.

CORD-FASTENER.

No. 877,428.

Specification of Letters Patent.

Patented Jan. 21, 1908.

Application filed January 26, 1907. Serial No. 354,331

To all whom it may concern:

Be it known that I, CHARLES V. HUGO, a citizen of the United States of America, residing at St. Louis, in the county of St. Louis 5 City and State of Missouri, have invented new and useful Improvements in Cord-Fasteners, of which the following is a specification.

This invention relates to cord fasteners, 10 and one of the principal objects of the invention is to provide a cord fastener of simple construction which can be conveniently used as a paper clip or a book mark.

Another object of my invention is to provide a simple and efficient cord fastener for securing the ends of a cord or tape passed around a package of papers, letters or documents, and which will be easy and quick in operation and will hold the ends of the cord 20 firmly in fastened position.

These and other objects may be attained by means of the construction illustrated in the accompanying drawings, in which:

Figure 1 is a perspective view of a cord or 25 tape fastener made in accordance with my invention. Fig. 2 is a perspective view of a package of papers or documents secured together by a tape, the ends of which are connected to a fastener made in accordance with my invention. Fig. 3 is a detail perspective 30 view of my tape or cord fastener in use as a book mark. Fig. 4 is a rear elevation of an envelop having a cord passed around the same and secured to a cord fastener made in 35 accordance with my invention. Fig. 5 is a detail view illustrating the rear portion of the envelop flap opened out with my fastener secured thereto. Fig. 6 is a side elevation 40 of a roll of papers secured together by a cord and a fastener made in accordance with my invention.

Referring to the drawings for a more particular description of my invention, the numeral 1 designates a loop formed in one end 45 of the fastener which is formed of a single piece of resilient wire of the proper gage and resiliency, the terminal ends of which form said loop 1, and the parallel members 2 are extended from said loop backward to form 50 the two coils 3, said coils comprising two or more convolutions which are connected by a cross strand 4, said strand 4 passing between the parallel members 2, as shown more particularly in Fig. 1. In using my fastener, as

shown in Fig. 2, a length of tape 5 is secured 55 in the loop 1 by an ordinary knot and the tape is passed around a package of papers or documents 6, and connected between the coils 3 of the fastener, and extended thence around the package and the free end 7 is secured 60 between the coils 3 at the opposite side of the fastener. When the device is to be used as a book mark, one of the members 2 is disposed upon one side of the leaf and the other one upon the other side thereof, as 65 shown in Fig. 3, and the coils 3 of the fastener engage the outer edge of said leaf. For securing a number of papers together, 70 the fastener or clip is utilized in a similar manner, the papers being secured between the two members of the coils 3 in an obvious manner. For securing an envelop, as shown 75 in Figs. 4 and 5, the fastener may be connected to the flap of the envelop by means of a staple or bent wire 8 passing through the flap of the envelop and connected to the loop 1, a cord or string 9 being secured to the loop 1 and passing under the staple or bent wire 8 is thus secured to the flap of the envelop, the string 9 then being passed around 80 the envelop and connected to the coil 3 at the right of Fig. 4, and extended thence around the envelop longitudinally and the free end of the cord connected to the coil 3 at the left of Fig. 4. As shown in Fig. 6 the 85 cord 9 is connected to the loop 1 of the fastener and passed around the wrapper 10 and the free end of the cord secured to one or both of the coils 3.

From the foregoing it will be obvious that 90 a paper fastener made in accordance with my invention may be utilized for the various purposes referred to, and provides a simple and efficient means for securing the free ends 95 of tapes or cords passing around packages of papers or an envelop, and as a convenient means for marking a place in a book, and as a paper clip.

Having thus described the invention, what I claim is:

1. An envelop fastener made from a single 100 length of spring wire and comprising parallel members bent at their ends to form a loop, oppositely disposed coils connected by a cross bar passing between said members, and 105 said members adapted to be secured upon opposite sides of an envelop flap by a wire staple passing through said loop and flap,

and a cord connected to said loop and staple to be connected to said coils, substantially as described.

2. A fastener of the character described composed of a single length of spring wire provided with parallel members, oppositely disposed coils connected by a cross bar extending between said members, and each end of the wire being bent into a loop, and a

cord or tape connected to said loop and 10 adapted to be connected to said coils, substantially as described.

In testimony whereof, I affix my signature in presence of two witnesses.

CHARLES V. HUGO.

Witnesses:
